United States Patent Office

Des. 182,621

Patented Apr. 22, 1958

182,621

POCKET FLASHLIGHT

Nolan Rhoades, Beloit, Wis., assignor, by mesne assignments, to The Electric Storage Battery Company, Philadelphia, Pa., a corporation of New Jersey

Application July 13, 1956, Serial No. 42,247

Term of patent 14 years

(Cl. D48—24)

The end of the flashlight not shown has a flat surface which is slightly recessed.

I claim:

The ornamental design for a pocket flashlight, as shown and described.
